Attorney.

UNITED STATES PATENT OFFICE.

ALBERT HARRIS, OF DENVER, COLORADO, ASSIGNOR OF ONE-HALF TO SANFORD CALDWELL, OF DENVER, COLORADO.

VALVE-GEAR.

1,252,692.

Specification of Letters Patent.

Patented Jan. 8, 1918.

Application filed March 30, 1917. Serial No. 158,573.

To all whom it may concern:

Be it known that I, ALBERT HARRIS, a citizen of the United States, residing at Denver, in the county of Denver and State of Colorado, have invented certain new and useful Improvements in Valve-Gears; and I do hereby declare the following to be a full, clear, and exact description of the invention, such as will enable others skilled in the art to which it appertains to make and use the same.

This invention relates to valve gear more particularly intended for use on internal combustion engines; and it consists in the novel construction and combination of the parts hereinafter fully described and claimed.

In the drawings, Figure 1 is an end view of portions of an internal combustion engine, partially in section, and provided with a valve gear according to this invention. Fig. 2 is a longitudinal section through the valve gear, drawn to a larger scale. Fig. 3 is a side view of the valve spindles or rods showing the crankshaft in cross-section. Fig. 4 is a plan view of the lever mechanism.

The engine has a power cylinder 2, and a piston 3 which works therein and drives a crankshaft 4 which works in a hollow frame 5. The cylinder 2 has an exhaust port 6 near its front end which is uncovered by the piston to effect the exhaust. An exhaust fan or pump of any approved construction is connected to the exhaust port 6, so that a partial vacuum is produced in the cylinder when the exhaust port is uncovered. An air admission valve 7 is provided at the rear end of the cylinder, and this valve is opened so as to let the exhaust fan or pump draw a current of pure air through the cylinder to expel the products of combustion. This exhaust fan or pump is not herein more fully described as any approved device for exhausting the contents of the cylinder can be used.

An admission valve 8 for gas or inflammable vapor is provided at the rear end of the cylinder, and it closes a seat 9 on a gas

chamber 10 on the cylinder. The gas is supplied under a low pressure to the gas chamber 10 in any approved way. The stem 12 of the gas valve slides in a guide 14 on the top of the gas chamber 10, and the stem 12 is hollow so that it forms an air passage 15.

The air valve 7 closes a seat 16 at the bottom of the passage 15, and its stem 17 is slideable in a guide 18 secured in the projecting upper end portion of the tubular valve stem 12. This guide or stem, or both of them, have air inlet holes 19.

The air valve 7 is operated by means of a lever 20, the middle part of which is pivoted to a rocking fulcrum rod 21 by a pin 22. The lower part of the fulcrum rod 21 is pivoted to the cylinder or other stationary support by a pin 23. The lever 20 is formed in two parts which straddle the eye of the fulcrum rod, and one end portion of it is pivoted to the stem 17 of the air valve by a pin 24. The other end portion of the lever 20 is pivoted by a pin 25 to the rod 26 which operates the air valve.

A casing 28 is secured to the crankshaft casing, and a cylindrical guide 29 is secured in this casing. A tubular rod 30 is provided for operating the gas valve 8, and this rod 30 slides longitudinally in the casing 28. The rod 26 slides inside the rod 30, and its lower part has an enlargement 31 which is secured to it by screwthreads 32. This enlargement 31 slides longitudinally in an enlargement 33 of the rod 30 to which it is secured by screwthreads 34.

The enlargement 33 slides in the guide 29, and it has a piston 35 on its lower end which slides in and closes the lower end of the casing 28. The lower end portion of the enlargement 31 has a stem 36 secured in it, and this stem carries a housing 37 in which a roller 38 is journaled. The crankshaft 4 has a cam 40 secured on it, and, as the crankshaft revolves in the direction of the arrow in Fig. 3, this cam engages with the roller 38 and pushes up the air valve rod 26, and opens the air valve. It is timed to do this when the piston uncovers the exhaust port,

so as to admit pure air to take the place of the products of combustion which are sucked out of the cylinder by the exhaust fan.

The tubular enlargement 33 of the rod 30 has a housing 41 secured to its lower end, and two rollers 42 are journaled in this housing. The crankshaft 4 has two cams 43 secured on it, and these cams push up the rod 30, after the air valve has been open for a sufficient length of time, and open the gas valve 8.

The upper end portion of the rod 30 is pivoted to one end portion of a lever 45 by a double-eye 46 and pins 47. This lever 45 is made in two parts which are spaced wider apart than the two parts of the air lever 20, and its other end portion is pivoted to the tubular stem 12 of the gas valve by pins 48. The middle part of the gas lever 45 is pivotally connected to the pin 22 at the upper end of the fulcrum rod 21 by links 49 and pins 50.

The air rod 26 and the gas rod 30 are moved downwardly by any approved means. In the example shown, the casing 20 is divided into two chambers 51 and 52 by a partition 53 which also affords a support for the guide 29. A spring 54 is shown in the lower chamber 51 between the partition 53 and the piston 35, for pressing the gas rod downwardly, but compressed air may be used instead of the spring, or both compressed air and spring may be used. A branch pipe 55 is shown for the admission of compressed air to the chamber 51.

A spring 56 is also shown in the upper chamber 52 for pressing the air rod downwardly. This spring 56 is arranged between a cap 57 at the top of the chamber and a piston 58 which is slideable in the chamber, and which is suitably secured to the enlargement 31 of the air rod 26. A branch pipe 59 is shown for admitting compressed air to the chamber 52, when compressed air is used in addition to the spring 56, or instead of it. When compressed air is not used it is not necessary for the piston 58 to fit the chamber 52, as it merely has to form an abutment for the spring.

In carrying out this invention, a series of similar engines is provided, and the engines are arranged so as to work to the best advantage, and the crankshaft is provided with cranks arranged at suitable angles to each other, and driven by the engines pertaining to them. The gas is admitted through the gas valve under low pressure to mix with the air in the engine cylinder, after the piston has closed the exhaust port, and the gas valve is closed as soon as sufficient gas has been admitted, so that the mixed gas and air may be compressed in the cylinder during the latter part of each back stroke. The mixture is ignited at the commencement of each forward stroke by any approved igniter or spark plug.

The connection of the piston 58 with the inner tubular rod 31 is effected by means of a key 60 which fits snugly in key-ways or slots cut in the said parts, and which is slideable longitudinally in elongated slots 61 in the outer tubular rod 33. The piston 58 is arranged to slide freely upon the said outer tubular rod 33.

What I claim is:

1. In a valve gear, a gas valve and an air valve provided with longitudinally slideable concentric stems, two operating levers pivoted at one end to the said valve stems, pivoted supporting devices pivoted to the middle parts of the said levers and permitting them to move crosswise of the valve stems and independently of each other, and means for operating the said valves independently of each other connected to the other ends of the said levers.

2. In a valve gear, a gas valve and an air valve, a pivoted fulcrum rod, links pivoted to the fulcrum rod, two operating levers having their middle portions pivotally supported by the said fulcrum rod and links, said levers being pivotally connected with the said valves at one end, and means for operating the said valves independently of each other connected to the other end portions of the said levers.

3. In a valve gear, a gas valve and an air valve provided with concentric stems, a pivoted fulcrum rod, a lever pivoted at its middle part to the free end portion of the fulcrum rod and having one end portion pivoted to the inner valve stem, links pivoted to the fulcrum rod concentric with the said lever, a second lever pivoted at its middle part to the said links and having one end portion pivoted to the outer valve stem, and means connected to the other end portions of the said levers and operating them at intervals to open the valves.

4. In a valve gear, a gas valve and an air valve provided with concentric stems, two pivoted operating levers connected to the said stems, two valve rods arranged concentrically and operatively connected with the said levers, a stationary casing provided with a guide for the outer valve rod to slide in and having a partition which divides it into two chambers arranged end to end, abutments secured to the respective valve rods and arranged in the said chambers, closing springs arranged in the said chambers and bearing against the said abutments, and means for sliding the said rods longitudinally to open the valves against the pressure of the said springs.

5. In a valve gear, a gas valve and an air valve provided with concentric stems, a pivoted fulcrum rod, a lever formed of two parts which straddle and are pivoted to the free end portion of the fulcrum rod and having one end portion pivoted to the inner

valve stem, links pivoted to the fulcrum rod concentric with and straddling the said lever, a second lever formed in two parts spaced wider apart than the parts of the 5 first said lever and having its middle part pivoted to and straddling the said links and having one end portion pivoted to the outer

valve stem, and means connected to the other end portions of the said levers and operating them at intervals to open the valves. 10

In testimony whereof I have affixed my signature.

ALBERT HARRIS.
